METHOD OF TREATING ASPHALTIC OILS.

1,399,792.

Specification of Letters Patent. Patented Dec. 13, 1921.

Application filed September 27, 1917. Serial No. 193,420.

To all whom it may concern:

Be it known that we, PAUL PRUTZMAN and GUY L. GOODWIN, citizens of the United States, residing at Santa Maria, in the 5 county of Santa Barbara and State of California, have invented certain new and useful Improvements in Methods of Treating Asphaltic Oils, of which the following is a specification.

- 10 The hereinafter described invention relates to a method adapted more particularly for the treatment of the California asphaltic liquids, such as petroleum, although, its use is not restricted or limited to the treatment 15 of asphaltic oils obtained in the State of California, and the same is a method of producing a single fractionation without without heat decomposition, which decomposition usually results from the present 20 methods employed for the treatment of such asphaltic oils, and the commercial products which suffer most depreciation in value from such decomposition, are lubricating oils, road oils and asphalts; the present invention 25 being more particularly applicable for the manufacture or production of the three mentioned products of the asphaltic oils, although the invention is not limited to the production of such materials, but provides a cheap and desirable 30 means for accomplishing a reduction or a single fractionation of any mixture of hydrocarbons, excluding only such as have an appreciable vapor pressure at normal temperatures, although, the invention may of 35 course be applied to such materials as contain a moderate proportion of volatiles, by first removing such, by other means of distillation.
- 40 The basic or underlying principle of the present invention, is, the treatment of the hydrocarbon liquids by the passage or flow of hot combustion products over the exposed surface of a sheet, film or mass of the asphaltic material to be fractionated, whereby the following important desiderata are gained, viz: a high degree of fuel economy, due to the exceptionally favorable heat cycle; avoidance of decomposition, due to 45 the low temperature and time factors following from the use of a large relative vol-
- ume of dry gas supplied; and low cost of maintenance, which results mainly from the fact that no heat is transmitted through metallic walls. 55
- The principle of the present invention may be applied to either a moving mass of liquid hydrocarbon, or to a mass at rest. Where applied to a moving mass, the hydrocarbon liquid or mass must be moved or flow 60 in a direction contrary to the flow of the hot gases, in which case, the process becomes a continuous one, inasmuch as a fresh supply of inflowing raw material is resorted to, to maintain the flow of liquid, and, in this case, 65 the process is single fractioning, as the vapor is removed in one cut and cannot be fractionally condensed, although, the process may be adapted to step distillation, which is multiple fractionating. Where the invention 70 is applied for the treatment of a mass of asphaltic liquid at rest, the process becomes an intermittent distillation, and as such, is multiple fractionating. In carrying out the invention, it must be understood, 75 that all fire gases are not applicable for such purpose, but only such as show a proper analysis suitable to the work to be done. In case the required resultant product is air blown asphalt, then fire gases showing 80 from 5% to 10% of excess oxygen may be used to advantage, and which produces an asphalt having a large demand for special purposes but the distillates resulting from the treatment are worthless, except for fuel, 85 due to oxidation of the vapor which takes place.
- Where the invention is employed for the manufacture of lubricating distillates or any other products which are to be treated 90 or filtered, then the fire gases should be approximately free from oxygen, although, it is possible to carry a trace of carbon monoxide, though if any large amount appears the fire is likely to be yellow or smoky and 95 will contaminate the products with soot.
- While no particular fuel nor form of generator are required, still whatever type is used must be capable of close regulation without undue attention, and it is preferable 100 to supply the air under slight pressure, so that an outward pressure of say 0.5" of

water may be held on the generator. In case there is an inward pressure, as there must be where the air supply is aspirated in, it is preferable to incase the generator in a

5 light metallic shell, so as to provide against air leakage.

The fire gases are not to be brought into contact with oil at a temperature of the generator, but at a lower temperature, but 10 which temperature is variable following the character of the oil and the type of the generator employed, but 1000 degrees F. at the evaporator inlet may be taken as a safe maximum.

15 To obtain the necessary reduction in temperature we may proceed in three ways, viz: radiation, dilution or absorption.

Radiation into the air of the excess heat reduces the fuel efficiency to that of a cylindrical still; and cannot be considered from 20 an operating standpoint.

Dilution is simple, easy to control, reasonably efficient, and has the great advantage of increasing the volume of dry gas atmosphere. 25 Either cooled gas from the discharge of an apparatus, or wet steam, may be used. The latter shows a lower fuel efficiency, when the heat required for evaporation of the water is included. Dilution by means of 30 either steam or gas is the plan best adapted to small installations.

Absorption of the excess heat in doing useful work raises the fuel efficiency to a very high point, and either alone or in combination 35 with dilution is the plan best adapted to large installations. A portion of the heat may be transferred to the entering oil, which may safely and advantageously be preheated to a temperature sufficient to 40 evaporate any water, thus avoiding frothing or spattering in the evaporator. But approximately only $\frac{1}{3}$ to $\frac{1}{2}$ of the temperature drop may be so utilized, and the balance must be absorbed in steam generation, or 45 taken care of by dilution.

The vapors from whatever type of evaporator (continuous or intermittent) is used should pass first to a scrubber. This may be a shell of roughly $\frac{1}{4}$ the cubic capacity of the 50 evaporator, in which the gas-vapor mixture is sufficiently slowed down to allow the separation of any coarse particles of raw material which may have been accidentally carried over, and the scrubber must be insulated 55 to prevent loss of heat by radiation, as any distillate condensed here has to be redistilled.

The gas-vapor mixture should be cooled to condense the vapor, and the condensate 60 moved from the gas. Cooling is simple, and may be accomplished in any type of condenser, air or water cooled. It is highly essential, however, to cool to the lowest possible temperature, if any volatile elements exist in the raw material, as because of the par-

tial pressure of the gas, losses will result if the cooling stops at a temperature where any of the constituents of the condensate have any vapor pressure.

Removal of the condensate from the gas is 70 a more difficult matter, but we have discovered a satisfactory method for accomplishing such removal, this being to centrifuge at a high velocity. A straight, or better, a curved vane centrifugal fan is highly suited 75 to this use, and may be so connected as to provide for aspiration, and for returning the spent gas required for moderating fire gas temperature.

The point and manner of application of 80 the centrifugal effect are of importance. If the distillates to be removed are relatively nonviscous, then the fan should be put at the end of the system, beyond the condenser, as thus it handles a smaller volume, and cold 85 gas only. But so located, if any very viscous distillates are run, they are quite likely to emulsify in the condenser, and in that condition separate the water of combustion very slowly. For such oils the fan should be 90 placed between the scrubber and the condenser, and sufficient air cooling provided between the scrubber and condenser to condense the distillate but not the water, leaving 95 this to be taken care of by the condenser.

In either situation the effectiveness of the fan as a centrifuge is much increased by reducing the velocity of the gases just prior to entry into the fan. This is accomplished by an enlargement of the vapor line, which also 100 provides the necessary air condensing surface. The reduction in velocity appears to allow time for the finer particles to coalesce, thus increasing their tendency to gravitate out of the gas.

The essential object of the present invention is, the treatment of the asphaltic liquid for the production of a single fractionation and this without a previous cracking of the oil being resorted to in the treatment of petroleum for the fractionation thereof and without the splitting of the oil to be treated and the spraying of the same into a vaporizing chamber.

Any suitable form of apparatus may be 115 employed for carrying out the method of treatment, but in the accompanying drawing, we have shown a simple apparatus for use in connection with the invention.

Referring to the drawings, wherein is 120 illustrated a longitudinal sectional view of an apparatus designed for the carrying out of the present invention, the method will be readily understood by a description thereof.

Gas or oil fuel under pressure, enters the burner 1, from the fuel supply pipe 2, and the air under pressure or aspirated, as preferred, is admitted by the pipe 3, to the said burner, the fire flame from the burner enter- 130

ing and filling the fireclay tube 4, which is incased in the metal jacket 5, while the spent gas or steam enters the annular space 6 surrounding the metallic jacket 5, through the controlled valve 7, and after taking up such heat as may be conducted through the fireclay wall enters the tube 4, at the bottom thereof, through the vents 8, the quantity of gas so admitted, into the tube 4, being regulated or controlled by the valve 7, according to the temperature desired at the top of the tube 4.

The fire gases ejected from the tube 4 are conveyed by the pipe 9 into the evaporator at a point adjacent the bottom thereof, while the raw oil or liquid hydrocarbon to be treated is admitted under pumping pressure into the upper end of the evaporator through the oil supply pipe 11, the oil or liquid to be treated discharging therefrom, onto the upper or top oil receiving plate or pan 12, there being a series of such plates or pans horizontally disposed within the evaporator 10. When the oil delivered onto the upper plate 12, completely fills the same, the excess oil overflows, and gravitates onto the next plate of the series of plates and from this plate onto the one arranged therebelow and so on throughout the series of plates, it being understood that the plates are arranged in staggered and vertically disposed relation. The oil reaching and filling the bottom plate of the series of plates 12, overflows to the bottom of the evaporator 10 whence it passes out through the trapped outlet pipe 13. During the downflow through the evaporator of the hydrocarbon liquid to be treated, the same encounters an upflowing stream of hot products of combustion, which is discharged from the tube 4, into the evaporator adjacent the bottom portion thereof through the discharge pipe 9, and passes upwardly through the evaporator to the upper end thereof and during the said upward flow of the hot products of combustion, the same pass around and over the plates 12, arranged therein, heating the oil within the plates or pans and flowing over the said exposed surfaces thereof absorbing the vapors therefrom. The oil or liquid hydrocarbon as it flows downwardly over the plates 12, within the evaporator is progressively heated and evaporated and by properly regulating the temperature and quantity of the fire gas admitted into the evaporator and the rate of oil feed of the oil or liquid hydrocarbon discharging into the evaporator, any desired degree of distillation and reduction may be produced.

In the type of evaporator disclosed in the drawings, the oil supporting plates 12 are affixed to a vertical rod 14, which at its lower end rests on and is supported by a bracket 15 within the evaporator 10, and the stag-

gered arrangement of the plates 12 is such that they do not touch or come in contact with the inner wall surface of said evaporator. The rod 14, is removable from within the evaporator on the opening or removal of the cover plate 16, of the evaporator, so that when the plates 12 have accumulated sufficient mineral sediment to interfere with the free flow of the oil or liquid hydrocarbon to be treated, the said plates 14, to which they are held and a clean set of plates substituted therefor.

The mixture of gas and vapor produced within the evaporating chamber pass directly therefrom into the outlet pipe 17', leading from the discharge outlet of the chamber and are conveyed thereby into the scrubber 18, flowing beneath the vertically disposed baffle plate 19, located within the said scrubber and then flowing upwardly and escaping from within the scrubber through the outlet 19' into the uppermost of a series of connected pipes 20. At its bottom the scrubber is provided with a trapped outlet, through which the residue and dirty oil deposited is withdrawn, and which oil so withdrawn may be returned to the feed pipe for the crude oil for redistillation. The velocity of the gases escaping from the scrubber into the first of the series of pipes 20 is suitably reduced, due to the fact, that these pipes are of a greater diameter than that of the pipes 9 and 17, so that the temperature drops by expansion to a sufficient degree to reduce the vapor to the form of a mist, the water vapors however, not being condensed. This mist passes through, and in fact, is drawn through the series of pipes 20, by means of a centrifugal 22, where the oil particles are centrifuged out and flow in a stream under pressure together with the gas and water vapors into the condenser 23, which condenser is maintained cold by the water entering the chamber 24, through the inlet 25 and escaping therefrom through the outlet 26, the condenser 23 being thus water jacketed. In this condenser, the water vapor is condensed and any remaining traces of oil are also liquefied, and the total distillate and water flowing from the condenser through the trapped outlet pipe 27, while the cold gases rise within the outlet pipe 28, provided for such gases, and escapes through the valve controlled pipe 29, the outlet being regulated by the valve 30, situated within said pipe.

It will be understood that the centrifugal fan 22 maintains a slight vacuum on the entire system back to the fireclay tube 4, the extent of said vacuum being regulated by the valve 31, interposed within the connection between the lowermost tube 20 and the centrifugal chamber 22', the said fan also holding a slight pressure on the condenser 130

23, and the pipes 28 and 32, and whatever of the spent gas may be required for controlling the temperature in the pipe 9 is taken from the pipe 32, the flow of the same being regulated by the valve 7, interposed within the pipe 32, at or near the top of the annular chamber 6, surrounding the shell 5 of the fireclay tube 4. The excess spent gas escapes through the valve controlled out-
10 let 29.

As before stated, any suitable type of apparatus may be employed for carrying out the invention, but preference is given to such a construction as will permit of a continuous down flowing stream of liquid hydro-carbon being subjected to the action of an ascending stream flow of hot products of combustion, which products of combustion are brought in intimate contact with the flowing mass of the liquid hydrocarbon so as to thoroughly heat the same and absorb the vapors therefrom. An apparatus may be employed whereby the liquid hydrocarbon to be treated is held and maintained at rest within a suitable receptacle, and the hot combustion products brought into direct contact with the exposed surface of the said liquid and by such flow action heating the mass of liquid oil and absorbing therefrom the vapors, and for this purpose, if so desired, the hot products of combustion may be forced upwardly through said mass of crude material.

The invention set forth resides in a single fractionation of the liquid hydrocarbon and this irrespective of the means employed, so long as the liquid hydrocarbon to be fractionated is not confined within metallic walls, through which walls the heat of the hot products of combustion is transferred, and the invention is more specifically designed for the production of lubricating oils, road oils and asphalts and has no particular concern with what subsequent treatment the separated volatile portions of the oil is subjected to.

By the use of the described invention, many advantages are realized over the methods now employed for the fractionation of liquid hydrocarbons, and which may be termed, heat interchanging systems, for instance: deposition of carbon on metallic transferring surfaces, and therefore over-heating and rapid depreciation is entirely obviated, deposits of soot, sediment or carbon due to the accidental over-heating may be confined to removable surfaces, thus reducing time and labor of cleaning to a nominal figure; decomposition due to over-heating of even the tenderest sulfur crudes may be entirely overcome, and the portion of the apparatus employed containing the actual fire is much reduced in volume, making effective insulation or regenerative jacketing possible, and it is possible by the use of the present proc-

ess to obtain products which are not obtainable from the same material by the processes at present employed, and this applies to distillates and residues.

It will be noted that by the use of our process the raw material to be treated is not discharged into a vaporizing chamber in the form of spray, but the raw material is acted upon, as a mass or sheet of oil, and as a matter of fact, every precaution is taken to prevent any portion of this sheet or mass from being accidentally detached and converted into a spray, inasmuch as the formation of a spray or an atomization of the raw material would defeat the object of the present process.

Having thus described the invention, what is claimed as new and desired to be protected by Letters Patent of the United States, is:—

1. The method of producing a single fractionation of liquid hydro-carbon without de-composition, which consists in subjecting the exposed surface of masses of liquid hydro-carbon to the direct action of hot products of combustion free from oxygen, reducing the temperature of the hot products of combustion and causing the same to flow over the liquid hydro-carbon in a counter direction to the flow of said masses for the heating thereof and absorbing the vapors therefrom.

2. The method of producing a single fractionation of liquid hydro-carbon without heat de-composition which consists in generating fire gases free from oxygen, reducing the temperature of these gases, subjecting the exposed surface of a confined flowing body of liquid hydrocarbon to the direct action of a counter-flowing stream of said gases for the heating of the traveling flow of liquid hydrocarbon and absorbing the vapors therefrom.

3. The method of producing a single fractionation of liquid hydrocarbon without heat decomposition, which consists in causing a stream of hot products of combustion freed from oxygen and reduced in temperature to flow counter to a confined flowing body of liquid hydrocarbon to heat the same and absorb the vapors therefrom, thence withdrawing the vapors and forcing the same through a condenser whereby the water and the oil contained within the vapors are liquefied and separated.

4. The continuous method of producing a single fractionation of liquid hydrocarbon without heat decomposition which consists in reducing the temperature of hot products of combustion freed from oxygen, subjecting the exposed surface of a confined mass of liquid hydrocarbon to the direct action of a stream of said products of combustion caused to flow equally over the mass of liquid hydrocarbon for the heating of

the liquid mass and absorbing the vapors therefrom, withdrawing the said vapors and forcing the same through a condenser for the separation of the water and the liquefying of any oil which may be contained within the vapors.

5. The continuous method of producing a single fractionation of liquid hydrocarbon which consists in subjecting an exposed surface of a mass of liquid hydrocarbon to the direct action of hot products of combustion caused to flow thereover for the heating of the liquid hydrocarbon and absorbing the vapors therefrom, thence causing the vapors to be passed through a scrubber, thence withdrawing the vapor from the scrubbers and subjecting the same in the form of a mist to a centrifugal for the centrifuging of the oil particles therefrom, and thence forcing the same, together with the gas and water contained therein in and through a condenser.

6. The method of producing a single fractionation of liquid hydrocarbon, which consists in subjecting the exposed surface of an undivided body of liquid hydrocarbon to the direct action of a flowing body of hot products of combustion free from oxygen and reduced in temperature for absorbing and reducing the vapors therefrom.

7. The continuous method of producing a single fractionation of liquid hydrocarbon, which consists in generating hot products of combustion free from oxygen, reducing the temperature of these gases, subjecting all portions of an undivided confined body of liquid hydrocarbon equally to the direct action of a flowing body of said temperature regulated hot products of combustion for removing from all portions of said liquid an equal and substantially predetermined proportion of volatile elements; forcing the removed vapors through a condenser for a separation of the water therefrom, and liquefying any oil which may be contained therein.

8. The method of producing a single fractionation of liquid hydrocarbon which consists in generating fire gases free from oxygen, reducing the temperature of these gases, applying the gases to the exposed liquid to be treated whereby to heat all portions of the liquid substantially equally thereby removing from all portions a substantially equal proportion of volatile elements and whereby to avoid carrying over with the generated vapors any material portions of non-volatile elements, cooling the mixture of spent gas and vapor to a temperature at which the vapors will be liquefied, and separating the condensed vapors from the accompanying non-condensable gases.

9. The continuous method of producing a single fractionation of liquid hydrocarbon which consists in generating hot gases free

from oxygen, reducing the temperature of these gases, applying the gases so reduced in temperature to the exposed surface of a mass of liquid hydrocarbon whereby to heat all portions of the liquid substantially 70 equally and thereby removing from all portions a substantially equal proportion of volatile elements, causing the vapors to pass through a scrubber, removing the vapors from the scrubber, and separating the condensed vapors from the accompanying non-condensable gases.

10. The continuous method of producing a single fractionation of liquid hydrocarbon which consists in subjecting an exposed surface of a mass of liquid hydrocarbon to the direct action of heated products of combustion caused to flow thereover for the heating of the liquid hydrocarbon and absorbing the vapors therefrom, subjecting the vapors to 80 a cooling medium and subjecting the same in the form of a mist to a centrifugal for the centrifuging of the oil particles therefrom, and thence forcing the same, together with the gas and water contained therein in and 85 through a condenser.

11. The continuous method of producing a single fractionation of liquid hydrocarbon, which consists in subjecting an exposed surface of a mass of liquid hydrocarbon to the direct action of hot products of combustion freed from oxygen and reduced in temperature, said products being caused to flow over said liquid hydrocarbon for the heating of the same and absorbing the vapors therefrom, thence causing the vapors to be passed through a scrubber, thence withdrawing the vapors from the scrubber and subjecting the same in the form of a mist to a centrifugal for the 95 centrifuging of the oil particles therefrom.

12. The continuous method of producing a single fractionation of liquid hydrocarbon, which consists in generating fire gases free from oxygen, reducing the temperature 100 of these gases, subjecting an exposed surface of a mass of liquid hydrocarbon to the direct action of said gases, the temperature of which has been reduced but is still hot, said gases being caused to flow over said exposed surface for the heating of the liquid hydrocarbon and absorbing the vapors therefrom, cooling the mixture of spent gas and vapor to a temperature at which the vapors will be completely liquefied, subjecting the same in the form of a mist to a centrifugal for the centrifuging of the oil particles therefrom, and thence forcing the same, together with the gas and water contained therein in and through a condenser. 115 120 125

In testimony whereof we have signed our names to this specification.
